UNITED STATES PATENT OFFICE

100,351

DESIGN FOR A FOUNTAIN PEN

Chozo Wada, Tokyo, Japan

Application February 12, 1936, Serial No. 61,103

Term of patent 3½ years

To all whom it may concern:

Be it known that I, Chozo Wada, a subject of the Emperor of Japan and residing at Tokyo, Japan, have invented a new, original, and ornamental Design for a Fountain Pen, of which the following is a specification, reference being had to the accompanying drawing, forming part thereof.

In the drawing, Fig. 1 is an elevational view of a fountain pen showing my new design with the

cap on the pen end of the barrel; Fig. 2 is a side view with the cap on the opposite end of the barrel; Fig. 3 a cross section on the line 3—3 of Fig. 1 and Fig. 4 a cross section on the line 4—4 of Fig. 1.

I claim:—

The ornamental design for a fountain pen as shown and described.

CHOZO WADA.
